DESIGN FOR A CARPET SWEEPER

Orson G. Burch, Highland Park, Mich.

Application October 26, 1934, Serial No. 53,773

Term of patent 14 years

To all whom it may concern:

Be it known that I, Orson G. Burch, a citizen of the United States, and resident of Highland Park, county of Wayne and State of Mich., have invented a new, original, and ornamental Design for a Carpet Sweeper, of which the following is a specification, reference being had to the accompanying drawing, forming a part thereof.

The figure is a view in perspective of a carpet sweeper showing my new design.

I claim:

The ornamental design for a carpet sweeper, substantially as shown.

Signed at Chicago, in the county of Cook and State of Ill., this 19 day of October, A. D. 1934.

ORSON G. BURCH.
